CLAIM

The ornamental design for a charger, as shown and described.

DESCRIPTION

FIG. 1 is a perspective view of a charger, showing our new design;

FIG. 2 is a perspective view of the charger;

FIG. 3 is a top plan view of the charger;

FIG. 4 is a bottom plan view of the charger;

FIG. 5 is a right side plan view of the charger, for which a left side plan view is identical;

FIG. 6 is a front plan view of the charger; and,

FIG. 7 is a rear plan view of the charger.

The broken lines in the figures depict portions of the charger which form no part of the claimed design.
